TOOL FOR CUTOFF AND THREADING OPERATIONS AND THE LIKE

Filed April 25, 1947

UNITED STATES PATENT OFFICE

2,514,146

TOOL FOR CUTOFF AND THREADING
OPERATIONS AND THE LIKE

William A. St. Jean, Detroit, Mich.

Application April 25, 1947, Serial No. 743,858

4 Claims. (Cl. 82—35)

1

The present invention relates to machine tools, and particularly to an improved tool construction especially designed for lathes and adapted to improve the performance of the lathe in cut-off operations and in the performance of such operations as grooving and threading, wherein difficulty is frequently encountered due to the tendency of the work to climb over the top of the tool, particularly where the work has considerable unsupported length in relation to its diameter. On account of this tendency, chatter and binding are frequently encountered in the use of cut-off tools of the varieties commonly used at the present time, and it is also often necessary to take a shallower cut or to use a lower rate of cross feed than would otherwise be feasible.

It has heretofore been proposed to use a tool steadyng device consisting of an arm adapted to overlie and to bear against the top of the rotating workpiece to prevent the workpiece from rising, and so to eliminate the objectionable tendencies previously mentioned.

Metal working lathes are quite universally constructed with a cross slide which travels in a horizontal plane, but the vertical distance between the top of the cross slide and the axis of the spindle varies in lathes of different manufacture as well as between lathes of different sizes. It is desirable also to vary the vertical position of the point of engagement between the cutting edge of the tool and the work, when cutting different types of material. For example, in performing a cut-off or similar operation upon a material such as brass, it is common to set the cutting edge to engage the work somewhat below the axis of rotation, while in cutting certain other types of materials, it is more usual to place the cutting edge somewhat above the axis. In order to permit standard types of cutting tools to be used under these varying conditions, and upon lathes wherein the vertical distance between the top of the cross slide and the axis of the spindle varies, lathes are commonly provided with a rocker structure or equivalent means whereby the cutting tool may be rocked about a longitudinal axis to permit the cutting edge of a tool carried thereby to be raised or lowered. It has been found that steadyng devices of the types known to the prior art are unsatisfactory under many of the operating conditions encountered in the performance of the above-indicated operations, and frequent breakage of either the steadyng device or the tool resulted, apparently from the tendency of the steadyng arm either to bind the work during the cross feed, or to free the work somewhat, per-

2

mitting the work to tend to ride over the point of the tool.

It is an important object of the present invention to eliminate the above-noted difficulties, and to provide a steadyng device which permits the tool to be fed into the work in a tilted position and with the point of the tool either above or below the spindle axis, if desired, without thereby unduly stressing either the tool, the work, or the steadyng structure.

An object related to that last stated is to provide an improved steadyng device of the indicated character having a tiltable steadyng shoe rockable about an axis transverse to the shoe and adapted to be set in a true horizontal position, or positioned parallel to the cross feed path, without regard to the angularity of the cutting tool, the arrangement being such that the shoe may be set in an approximate manner, merely by eye, and may then be adjusted by the mechanic during the performance of the cutting operation, the adjustment being effected simply by the "feel" of the parts during operation, so that accurate gaging or elaborate set-up methods are not required, despite which the above-noted difficulties and the frequent breakage of such devices constructed in accordance with prior known designs are eliminated.

Another object of the invention is to provide an improved tool holder of the character indicated incorporating novel, simplified and extremely rugged means for supporting the cut-off blade and the steadyng shoe means.

Still another object is to incorporate in a device of the character indicated, improved means for adjusting the position of the steadyng shoe means longitudinally with respect to the work, which adjusting means permits the shoe to be arranged either perpendicularly with respect to the axis of rotation of the work or at any desired angle within limits of adjustment, whereby the position of the steadyng shoe means may be altered to accommodate it to the configuration of the work and to permit the cut-off blade or other tool to operate close to a shoulder or other configuration without interference.

Other objects and advantages will be apparent upon consideration of the present disclosure in its entirety.

In the drawings:

Fig. 1 is a side elevational view of a tool-holding structure incorporating the principles of the present invention, corresponding to a transverse section through a portion of a lathe upon which the inventive structure is depicted as installed, the

work being illustrated in cross section and the cross slide of the lathe shown in side elevation;

Fig. 2 is a partial top plan view;

Figs. 3, 4 and 5 are sectional views taken substantially on the lines 3—3, 4—4, and 5—5, respectively, of Fig. 1 and looking in the direction of the arrows;

Fig. 6 is a perspective view of the shoe-supporting arm; and

Fig. 7 is a perspective view of the arm-supporting collar.

Referring now to the drawings, reference character 10 designates generally the cross slide of a lathe, which is not otherwise illustrated, since as will be appreciated, the details of construction of the lathe or other machine tool upon which the invention is employed form no part of my present invention and may be varied widely. The cross slide is adapted to be fed into and retracted from the work along the line designated 12 by suitable cross feeding means controllable by means of the hand crank 14. A tool post 15 is attached to the top of the cross slide 10 in any suitable or conventional manner as by means of the T-slot 20 and T-head 18 engaged in the slot 20, which is formed in the surface of the cross slide. The rocker assembly 16 permits the tool to be tilted about a longitudinal axis. A clamping screw 22 axially supported by and having a head portion 23 projecting above the post 15 is adapted to detachably fasten to the post a tool holder generally designated 24, the shank of which engages in a slot 25 in the post. It will be seen that the arrangement of these parts is also conventional in character and subject to variation without departure from the spirit of the invention.

The head portion 26 of the tool holder is provided with a horizontal slot 23 formed substantially centrally thereof and which is narrow vertically and extends entirely through the head to divide it into upper and lower sections 35, 36. A relatively shallow dovetailed tool-holding slot 32 is formed horizontally in one perpendicular face 30 of the head, adapted to receive a tool, shown as a conventional cut-off blade 34. It will be seen that the slot 32 is formed partly in each of the sections 35, 36. The vertical dimension of the slot 32 is such that the blade 34 may be readily placed in or removed from the slot when the upper and lower head sections 35, 36 are in their relaxed positioning. The sections 35, 36 may be forced toward one another, to clamp the blade 34 in place, however, by means of a combined clamping screw and post member 38 having a lower clamping screw portion 44 which extends vertically through the head and which is received in aligned, bored portions 40, 42 in the upper and lower head sections respectively. Screw portion 44 extends freely through the upper bore section 40, but such screw portion is threaded into suitably tapped threads formed in the lower bore section 42.

The clamping post 38 is also provided with an integral shoulder 45 overhanging the top section 35 of the head 26, while the upper portion 39 of the post is cylindrical and carries an integral squared or other suitably configured wrench-receiving head portion 46. It will be seen that by virtue of this arrangement the post may be turned in such direction as to force the shoulder 45 against the top section 35 while the lower section 36 is drawn upwardly by the screw-threaded portion 44, the two sections 35, 36 being thereby forced together to clamp the blade in position.

The cylindrical portion 39 of the post carries

a clamping collar bracket 48 which is vertically split upon one side as indicated at 50, the split sections being adapted to be drawn together by a clamping screw 52 in such manner that when the screw is tightened the collar bracket 48 is rigidly held upon the post, while when the screw is loosened, the collar bracket may be moved vertically along the post for adjustment. The collar bracket swingably supports an arm 54 which projects horizontally therefrom, the end of the arm adjacent the collar being contoured to describe a partly cylindrical convex surface. The collar bracket 48 is provided with a corresponding partly cylindrical concaved seat 56 against which the convex end of the arm 54 seats, these parts having a common vertical axis which is the locus of a screw 60 which pivotally connects the arm to the collar. It will be seen that a forwardly projecting supporting portion 58 formed integrally with the collar bracket 48 projects outwardly from the latter beyond the concaved seat portion 56 and underlies the rounded rear end 55 of the arm 54. The screw 60, which is smooth except at its lower end which threadedly engages bracket portion 58, extends through and accurately fits a drilled hole 62 extending axially vertically through the rounded extremity 55 of the arm 54. The opening 64 formed in the supporting bracket portion 58 is correspondingly axially disposed with respect to the cylindrically concaved seat 56. When the screw is loosened, the arm 54 may swing easily. These parts and the seat portions 55, 56 are accurately fitted and closely engage one another, so that the seat portions may take the load of force transmitted upwardly through the shoe and arm even when the screw is tightened to hold the arm against swinging. The arm 54 preferably tapers to decreasing width toward its outer end and is adapted to overlie a workpiece as W mounted in the lathe.

A shoe 70 is supported by and beneath the arm 54 and may be of similar tapering configuration, viewed in plan. The shoe is preferably provided with a hardened bottom or wear plate portion 72 and is so supported that it may be tilted about a longitudinal axis. The inner end of the shoe is provided with a pair of laterally spaced upwardly extending pierced lug portions 73, 74 which extend upon opposite sides of a centrally disposed downwardly projecting tongue or lug portion 75 carried by the arm 54, a pivot pin 76 being provided extending through all of the lug portions 73, 74, 75. An adjusting and reaction screw 78 is threaded in a suitably tapped hole 80 extending vertically through the arm 54 near its end, the lower extremity of the screw engaging the top of the shoe 70. If desired, a certain amount of frictional resistance may be provided tending to oppose turning of the screw 78, as by forming a longitudinal slot 82 extending vertically between the free end of the arm 54 and the hole 80, the split ends which are thereby defined being slightly pressed together so that the screw is frictionally gripped between them yet may be easily turned by a wrench whenever desired.

The head portion 26 is shown as provided with a screw 85 threaded in a suitably tapped vertical opening (undesignated) extending through the top section 35 of the head, the lower extremity of the screw bearing against the upper surface of the lower section 36 of the head. Screw 85 thus limits movement of the sections 35, 36 toward one another and prevents their being clamped so tightly by the screw post 38 as to

distort their relaxed positioning. It is also possible to somewhat spread the jaws by means of the screw 85 to permit the acceptance of a blade of somewhat greater vertical dimension by the slot 32, or to enable the jaws to be spread if they have become distorted due to carelessness as by being clamped together too tightly with the screw 85 loosened so completely that it fails to afford the intended protection against springing of the jaws.

It is believed that the manner of using the invention will be apparent to those skilled in the art from the foregoing description, although it may be helpful to summarize briefly the operation and some of the operative considerations involved in the design. Where the dimensions of the lathe are such that the cutting blade may be mounted in a horizontal position as shown in the drawings, with the cutting edge in horizontal alignment with the axis of rotation of the work, since post 38 is then in vertical position, the shoe 70 is also adjusted to horizontal position by means of the screw 78, and the collar 48 is placed in a position such that the bottom of the shoe bears against the top of the work as shown in Fig. 1 when the screw 52 is tightened. The shoe is thus rigidly held in this position, and any tendency of the work to climb with respect to the cutter as the work rotates in the direction of the arrow 84 is opposed by the shoe. Force applied to the bottom of the shoe is transmitted to the arm 54 through the screw 78 and through lugs 74, 75, the resultant tendency to rock the arm 54 upwardly placing the bracket portion 58 in tension and the rounded seat portions 55, 56 in compression. The force is thus transmitted to the collar bracket 48 and post 38 to the head 26, which takes both the upward force upon the shoe and the downward force upon the cutter 34. A structure of such rigidity is thereby afforded that the tendency of the work to chatter or to climb over the top of the tool is eliminated.

As above pointed out, it may be desirable to tilt the cutting tool and rocker up or down somewhat, either because of the character of the work and the resultant advisability of placing the cutting edge somewhat above or below the axis of rotation, or due to the fact that the vertical distance between the top of the cross slide and the axis of the spindle varies somewhat from the dimensioning for which the tool supporting assembly was designed. In either such event, the tool is fed horizontally into the work but the tool and the post 38 are somewhat tilted about the rocking axis of the rocker, and this tends to impart a corresponding tilt to the lower surface of the shoe 70. Such tilt of the shoe may be compensated, however, by so adjusting the screw 78 as to swing the shoe about the pin 76 to return the lower face of the shoe to horizontal position, or to a position parallel to the plane of movement of the cross slide. It will be seen that if the lower face of the shoe is horizontal, the feed will have no tendency to cause the shoe either to bind against or leave the work. As a practical matter, however, it is possible to adjust the shoe to a position as nearly horizontal as possible, judging simply by eye, and without the use of special gauging means. When thereafter the mechanic feeds the tool into the work, he may at the same time keep a wrench in engagement with the head of the screw 78 and tighten or loosen such screw as may be required during inward feeding of the tool to compensate for any undue tightness or looseness that may develop. He can detect the

need for such adjustment by the ease with which the screw 78 turns.

It will also be noticed that by virtue of the parallel arrangement of the screw 60 with respect to the axis of post 38 and the fact that angular adjustment may be made by swinging the collar 48 about post 38 as well as by swinging the arm 54 about screw 60, the arm assembly 54 and the shoe carried thereby may be moved longitudinally with respect to the work, to carry them bodily toward or from the tool while nevertheless permitting the shoe to be arranged at any desired transverse angle. Thus when a cut is to be made close to a shoulder or other irregular configuration upon the work, the shoe may not only be moved along the work to clear, but may be arranged at any of a wide variety of angles to provide the best support and permit working very close to the irregularly configured portion of the work.

It will be apparent that various changes and modifications may be made without departure from the fair and intended scope of the subjoined claims.

25 I claim:

1. A holding and steadyng device for cut-off tools and the like comprising in combination with a tool holder having a shank adapted to be mounted in a suitable support and having a head adapted to carry a tool, said head having longitudinally separated portions movable toward and from one another to selectively grip and release a forming tool, means for so moving said portions comprising a clamping member bridging and engaging both of said portions and actuatable to move the same toward one another, a stud portion extending substantially vertically upwardly from and formed integrally with said clamping member, a steadyng arm carried by said stud portion and projecting therefrom, and means for selectively securing said arm to said stud portion at any of various positions of vertical adjustment.

2. Means for supporting and steadyng a cut-off tool or the like comprising in combination with a tool holder having a shank adapted to be mounted in a suitable tool support, and having a head adapted to carry a work-forming tool, steadyng means carried by said tool holder comprising an arm carried thereby and projecting forwardly from the head at an elevation above that at which the tool is supported, whereby such arm may overlie work with which the tool is engaged, two substantially parallel and vertical pivot means connecting the arm to the tool holder, and locking means for each of said pivot means, whereby the arm may be adjusted both angularly and longitudinally.

3. Means for supporting and steadyng a forming tool during use thereof in a lathe or the like, comprising in combination, a tool holder having a shank adapted to be mounted in a suitable tool support and having a head, means carried by the head for removably securing thereto a forming tool, and steadyng means carried by said head comprising an arm supporting member carried by and extending upwardly from said head, an arm carrier mounted on and vertically movable with respect to said arm supporting member, said carrier being swingable about a vertical support axis with respect to said member, vertical pivot means carried by said carrier at a point spaced from the aforementioned axis, and a steadyng arm carried by said pivot means and swingable about both the support axis and the
